UNITED STATES PATENT OFFICE.

ALPHONSE FERNANDEZ, OF WASHINGTON, DISTRICT OF COLUMBIA.

TORPEDO-LAUNCHING APPARATUS.

1,235,782.

Specification of Letters Patent.

Patented Aug. 7, 1917.

Application filed September 20, 1916. Serial No. 121,249.

To all whom it may concern:

Be it known that I, ALPHONSE FERNANDEZ, a subject of the King of Spain, residing at the city of Washington, in the District of Columbia, have invented certain new and useful Improvements in Torpedo-Launching Apparatus; and I do declare the following to be a full, clear, and exact description of the invention, such as will enable others skilled in the art to which it appertains to make and use the same.

My invention aims to provide a simple apparatus for launching torpedoes in any direction from a submarine vessel while submerged and to this end the invention resides in certain novel features of construction and in unique combinations of parts to be hereinafter fully described and claimed, the descriptive matter being supplemented by the accompanying drawings which constitute a part of this application and in which:

Figure 1 is a vertical section, partly in elevation showing the normal position of parts when the launching apparatus is housed within an external compartment in the shell of the submarine;

Fig. 2 is a side elevation of the launching mechanism preparatory to discharging a torpedo, the coöperating parts of the vessel being shown in vertical section;

Fig. 3 is a side elevation, partly in section, of the launching apparatus immediately after ejecting a torpedo;

Fig. 4 is a horizontal section on the plane indicated by the line 4—4 of Fig. 1;

Fig. 5 is a vertical transverse section on the plane designated by the line 5—5 of Fig. 1;

Fig. 6 is a similar view on the plane indicated by the line 6—6 of Fig. 1, showing one of the torpedo clamps in operative position;

Fig. 7 is a duplicate of Fig. 6 with the exception that the clamp is shown in open position;

Fig. 8 is a plan view of the two sliding rods for releasing the clamping means and the ejecting means, showing more particularly the operating crank for sliding these rods;

Fig. 9 is a vertical transverse section on the plane designated by the line 9—9 of Fig. 1, showing more particularly the operating

means for the doors of the compartment in which the torpedo launching apparatus is normally housed, said doors being shown in closed position; and

Fig. 10 is a duplicate of Fig. 9 with the doors open.

Fig. 11 is a vertical transverse section on the plane of the line 11—11 of Fig. 1.

In the drawings above briefly described, the numeral 1 designates the shell of a submarine and 2 has reference to an external compartment of said shell, said compartment having doors 3 which when closed exclude water therefrom. At its opposite ends the compartment 2 is also equipped with doors 4 by means of which the torpedoes may be inserted into the launching apparatus which is normally housed in said compartment 2. Links 5 connect the doors 3 with vertical operating screws 6 having hand wheels or the like 7 on the interior of the vessel and in order that said links may offer no obstruction to inserting the torpedoes, they are bowed outwardly as depicted most clearly in Fig. 9.

Journalled at their ends in appropriate bearings carried by the bottom of the compartment 2 and by any appropriate superstructure 8 beneath said compartment are two vertical screws 9 having gears 10 on their lower ends meshing with another gear 11 which may be driven in either direction so as to simultaneously rotate the two screws 9. A cross head 12 is provided with threaded openings receiving the screws 9 so that as said screws are turned said cross head will be raised or lowered according to the direction of rotation of said screws. The cross head 12 is formed with central opening 13 alining with a stuffing box 14 on the bottom of the compartment 2, said opening and stuffing box receiving therein a hollow vertical shaft 15 having bearing collars 16 above and below said cross head, ball bearings 17 being preferably interposed between said collars and head. It will thus be evident that as the cross head 12 is raised the shaft 15 will be projected through the stuffing box 14 beyond the top of the vessel when the doors 3 are opened.

The upper end of shaft 15 has formed thereon a hollow head 18 to which approximately the center of a torpedo cradle 19 is

hinged at 20 for vertical adjustment. For so adjusting the cradle 19 a link 21 connects it with the upper end of a vertical rod 22 which passes through the hollow 5 shaft 15, said rod being swiveled at 23 to a vertical screw 24 having a hand wheel 25 disposed at the lower end of the shaft. By proper manipulation of the screw 24, therefore, the cradle 19 may be adjusted vertically around its hinge 20 after it is once projected from the compartment 2 by raising of the shaft 15.

The cradle 19 is preferably in the form of a half tube with tubular guides 26 extending along its edges and formed with longitudinal slots 27 in their inner sides. A pair of plungers 28 (see Fig. 4) are mounted slidably in the tubular guides 26 and by means of coiled springs 29 housed in said 20 guides, said plungers are adapted to be projected when released in the manner to be described. A stirrup 30 extends between the plungers 28 and when the latter are projected, the ends of said stirrup are adapted 25 to travel in the slots 27, said stirrup then serving to eject a torpedo T from the cradle 19. The stirrup 30 is preferably in the form of a pivotally mounted bail so as to swing downwardly when the plungers 30 28 have been reset to permit the insertion of another torpedo into the rear end of the cradle.

A forked arm 31 projects rearwardly from the lower side of cradle 19 and in its fork 35 the vertical shank of a plunger locking fork 32 is pivotally mounted, the arms of said fork cooperating with laterally projecting stops 33 on the rear ends of the plungers 28 as depicted clearly in Fig. 4, said arms being 40 adapted to be swung upwardly in front of the stop 33 when the plungers are retracted to hold the latter against the tension of the springs 29. For holding the fork 32 in operative position, a rigid finger 34 projects forwardly from the lower end of its shank and overlies a keeper 35 on the rear end of a release rod 36 which is slidably mounted in suitable bearings carried by the lower side of the cradle 19, a coiled spring 45 37 being provided for so shifting the rod 36 as to normally dispose the keeper 35 in operative position. The rod 36 terminates within the hollow head 18 and is here provided with a laterally extending finger 38 50 against which a vertical finger 39 on a horizontal crank arm 40 bears, said arm 40 being carried rigidly by the upper end of a vertical rock shaft 41 which passes through the hollow shaft 15. The lower end of shaft 60 41 is equipped with an operating lever 42 having suitable means 43 for locking it against movement when required. It will thus be observed that when lever 42 is operated in the proper direction finger 39 65 will force against 38 and will thus slide

rod 36 to release the finger 34 from keeper 35. This permits the springs 29 to project the plungers 28 to eject the torpedo T, the rear end of said torpedo being seated within the stirrup 30 as shown in Fig. 4.

70

A suitable number of clamps 44 are provided for holding the torpedo T in the cradle 19 until it is desired to release the same. Each clamp 44 consists of a pair of arms 45 extending around the cradle and having suitable springs 46 at their free ends for contact with the torpedo, said arms 45 being pivotally supported on a sliding rod 47 which is mounted in appropriate bearings carried by the lower side of the cradle 19, 80 the inner end of said rod abutting the end of the rod 36 as shown clearly in Fig. 8, whereby movement of 36 will be in turn imparted to 47. The rod 47 carries bolts 48 equal in number to the clamps 44, said bolts 85 being normally received between the angular lower ends 49 of the arms 45 so as to retain the springs 46 in forcible contact with the torpedo, a spring 50 being provided for yieldably holding said rod 47 in such position as to retain its bolts 48 in operative relation with the ends 49.

90

By the construction just described, it will be obvious that when the shaft 41 is rocked to shift rod 36 to release the plungers 28, the two clamps 44 will be simultaneously released, due to the fact that the bolts 48 are withdrawn. The springs 29 then eject the torpedo and the motor of the latter is automatically set in operation in the well known 100 manner. To insure that the clamps 44 open sufficient to prevent frictional contact with the torpedo, springs 51 shown in Figs. 6 and 7 are employed for opening said clamps.

100

The two clamps 44 are preferably disposed 105 at the front end of the cradle 19 as shown and although similar clamps may be employed at the rear end thereof, it is sufficient that a rigid loop 52 be provided at this location for holding the torpedo in 110 proper position and it is to be understood that said loop is of sufficient size to prevent it from in any manner retarding the movement of the torpedo when ejected.

115

For the purpose of preventing accidental discharge of the torpedo T while housed within the compartment 2, a fork 53 or an equivalent device is provided, said fork being shown as having a threaded shank received in a tubular nut 54 swiveled in the bottom of said compartment and having a hand wheel 55 on the interior of the vessel whereby said fork may be released and removed when it is desired to insert a torpedo into the apparatus through the front 120 end of the latter.

120

For the purpose of closing the clamps 44 after they have been released, to permit the bolts 48 to be again projected to operative position by their spring 50, jack screws 56 130

shown more particularly in Fig. 11 are threaded through the bottom of the compartment 2.

In operation, assuming that all parts 5 stand as shown in Fig. 1 with the torpedo T clamped in the apparatus by means of the clamps 44, and that the commander of the vessel wishes to discharge said torpedo, the screws 6 will first be operated to open 10 the doors 3 and this having been done, the screws 9 will be turned so as to raise the cross head 12 to slide the shaft 15 through the stuffing box 14, thus elevating the entire launching apparatus clear of the vessel. 15 The angle of the cradle 19 may now be adjusted by the hand wheel 25 and by turning the shaft 15 by means of a handle wheel or the like 15', the torpedo may be aimed in any required direction. All of this having 20 been done, the locking device 43 is released and the lever 42 is operated so as to cause the finger 39 to engage 38 and thus slide both rods 36 and 47 forwardly. These rods at approximately the same time, release the 25 fork 32 and the clamps 44 with the result that the springs 29 project the stirrup 30 to force the torpedo T from the cradle 19. The usual motor of the torpedo is set in 30 operation automatically in the well known manner as it leaves the cradle and said torpedo will therefore travel to its destination.

After firing the torpedo, the screws 9 are rotated to move the shaft 15 again downwardly so as to dispose the empty apparatus again in the compartment 2. The doors 3 are now closed and one or both of the doors 4 are opened to permit the water in the compartment 2 to drain therefrom. This having been done, by means of a suitable 40 mechanism, not shown, the stirrup 30 is grasped and withdrawn from the cradle, thus again placing the springs 29 under tension. The fork 32 which has in the meantime assumed the position shown in Fig. 3 45 is now returned to the position depicted in Fig. 2 and is locked in this position by sliding the rod 36 rearwardly until the keeper 35 underlies the finger 34. With the stirrup 30 now pendent from its pivots 50 as shown in dotted lines in Fig. 1, a torpedo may be inserted through the rear door 4, that is, the door adjacent the rear end of the apparatus, and may be thus properly located in the cradle 19, it being forced sufficiently forward to permit the stirrup 30 to be 55 again swung upwardly, after which said torpedo is again shifted rearwardly to seat it snugly within the stirrup. This having been done, the screws 56 are operated to 60 close the clamps 44 and when this occurs the bolts 48 are automatically forced between the lower ends of the arms 45 to retain said clamps in operative position. The doors 4 are now again closed and the apparatus 65 is then ready for the launching of

another torpedo whenever necessary. Before doing this, however, the screws 56 are preferably again released so that when the apparatus is reseated in the compartment 2 after firing another torpedo, the clamps 44 70 will not be closed prematurely.

When ever it is required to insert the torpedo T into the front end of the cradle 19, the operation is the same with the exception that the fork 53 is removed by means of the hand wheel 55. After the torpedo is positioned in the cradle, however, the fork 53 is again secured in place as shown in Fig. 4, and thus prevents the discharge of the torpedo while in the compartment 2 in 80 case the ejecting means should be released by injury caused by an enemy's shell, or otherwise.

The improved apparatus constructed as or substantially as shown and described will 85 be a highly efficient instrument of naval warfare and will readily permit the discharge of torpedoes on the surface of the water while the submarine carrying the improved mechanism is submerged, but the use of the invention is not limited to launching torpedoes on the surface since due to the fact that the device may be adjusted angularly in a vertical direction, torpedoes 90 may be sent to the surface from below or may be directed against enemy ships beneath the water line. It is also to be understood that although in the present case but one torpedo launching device is shown on the end of the shaft 15, any suitable number 95 of such mechanisms may be carried by said shaft and may be operated independently or in unison. Furthermore, although the ejecting means for the torpedoes is shown in the present embodiment of the 100 invention as actuated by spring means, it is obvious that a hydraulic or pneumatic ejecting mechanism could be employed.

I claim:

1. A torpedo launching apparatus comprising a torpedo cradle, means for clamping a torpedo in said cradle, means for ejecting said torpedo when the clamping means is released, a sliding bolt for holding said clamping means in operative position, a sliding rod for moving said bolt, and means for sliding said rod to release the bolt, the movement of said rod also serving to apply the ejecting means to use. 110

2. A torpedo launching apparatus comprising a torpedo cradle, means for clamping a torpedo in said cradle, means for ejecting said torpedo when the clamping means is released, a sliding bolt for holding said clamping means in operative position, a sliding rod for moving said bolt, a second sliding rod abutting the other and adapted for applying the ejecting means to use, and means for sliding said rods. 115

3. A torpedo launching apparatus com- 120

prising a torpedo cradle, means for clamping a torpedo in said cradle, spring actuated torpedo ejecting means, means for holding said ejecting means against operation, 5 and means for releasing said holding means and the clamping means at approximately the same time.

4. A torpedo launching apparatus comprising a torpedo cradle, means for clamping a torpedo in said cradle, spring actuated torpedo ejecting means, means for holding said ejecting means against operation, and one or more sliding rods for releasing said holding means and the clamping 10 means at approximately the same time.

5. A torpedo launching apparatus comprising a torpedo cradle, means for clamping a torpedo in said cradle, spring actuated torpedo ejecting means, means for holding 20 said ejecting means against operation, a sliding rod for releasing said clamping means, a second sliding rod for releasing said holding means, the two rods being in abutting relation, and means for sliding said 25 rods.

6. A torpedo launching apparatus comprising a torpedo cradle, a clamp for holding a torpedo in said cradle, said clamp consisting of a pair of arms passing around 30 said cradle and pivoted together, one end of said arms being adapted for engagement with the torpedo, and a bolt insertible between the other ends of said arms; in combination with torpedo ejecting means, and 35 means for withdrawing the bolt and applying the ejecting means to use at approximately the same time.

7. A torpedo ejecting apparatus comprising a torpedo cradle, a stirrup to receive 40 the rear end of the torpedo, spring means for projecting said stirrup, a vertically swinging locking member for holding said stirrup in retracted position, and a sliding keeper for holding said locking member in 45 operative position; in combination with means for clamping the torpedo in the cradle, and means for releasing said keeper and the clamping means at approximately the same time.

50 8. A torpedo launching apparatus comprising a cradle in the form of a half tube with tubular guides on its edges, said guides having longitudinal slots in their inner sides, a stirrup extending across said cradle 55 and passing through said slots, springs confined in said tubular guides for projecting said stirrup to eject a torpedo from the cradle, and means for normally holding said springs under tension and for releasing them 60 at will.

9. A torpedo launching apparatus comprising a torpedo cradle, a clamp at the front end thereof for holding a torpedo therein, a sliding rod beneath the cradle 65 and a bolt carried by said rod for holding

the clamp in operative position, spring means for ejecting the torpedo from the cradle, means for holding said ejecting means against operation including a second sliding rod beneath the cradle and abutting 70 one end of the other rod, and means for sliding the two rods simultaneously.

10. The combination with a submarine having a well in its upper side, of a torpedo cradle normally confined in said well, and a 75 single shaft passing slidably and rotatably into said well from the interior of the vessel and connected with the cradle for projecting it vertically from the well and swinging it horizontally when projected.

11. The combination with a submarine, of a shaft extending above the upper side thereof, a torpedo cradle mounted on the upper end of said shaft and having torpedo clamping means, torpedo ejecting means 85 carried by said cradle, and means for releasing the clamping means and ejecting means at substantially the same time from the interior of the vessel.

12. The combination with a submarine, of a shaft extending above the upper side thereof, a torpedo cradle mounted on the upper end of said shaft and having torpedo clamping means, torpedo ejecting means 95 carried by said cradle, and means for releasing the clamping means and ejecting means at substantially the same time from the interior of the vessel including a control therefor passing through the aforesaid shaft.

13. The combination with a submarine, of a vertical shaft extending from the top thereof, a torpedo cradle pivoted to the upper end of said shaft for vertical movement, means for swinging said cradle 105 around its pivot, and means for releasing the torpedo including coacting relatively fixed and movable members carried respectively by the shaft and cradle.

14. The combination with a submarine, of a vertical shaft extending from the top thereof, a torpedo cradle pivoted to the upper end of said shaft for vertical movement, means for swinging said cradle around its pivot, and means for releasing the torpedo 110 including coacting slidably engaged members carried one by the shaft and the other by the cradle.

15. The combination with a submarine, of a vertical shaft extending from the top 120 thereof, a torpedo cradle mounted on said shaft for vertical swinging, torpedo releasing means carried by said cradle and including a movable control member having a shoulder, a rock shaft rising through the 125 other shaft from the interior of the vessel, a crank arm extending laterally from the upper end of said rockshaft, and a vertical finger rising from said crank arm in sliding contact with the aforesaid shoulder.

16. The combination with a submarine having an external well and a door or doors for normally closing said well to exclude water therefrom; of an open-ended torpedo cradle normally confined in said well, means for projecting said cradle from the well, and a water-tight door leading into the well from the interior of the vessel in line with the open end of the cradle.

10 17. The combination with a submarine having a well in its upper side and a pair of hinged doors for said well to exclude water therefrom, an open-ended torpedo cradle normally confined in said well, a water-tight door leading from the interior of the vessel into the well in line with the open end of the cradle, and means for opening the aforesaid pair of doors including links bowed outwardly to prevent them from interfering with the insertion of a torpedo through said water-tight door into the cradle.

18. The combination of a submarine vessel, torpedo launching means, means for

moving said launching means bodily beyond the vessel, and means for permitting loading of said launching means from the interior of the vessel while the latter is submerged without permitting an inrush of water from the sea.

19. The combination of a submarine vessel having an external well, means for normally excluding sea water from said well, torpedo launching means housed normally in said well, means for projecting said launching means from said well, and means for establishing communication between the interior of the vessel and the well for loading the launching means while the vessel is submerged without permitting an inrush of water.

In testimony whereof I have hereunto set my hand in the presence of two subscribing witnesses.

ALPHONSE FERNANDEZ.
